UNITED STATES PATENT OFFICE.

SAMUEL J. WENTWORTH, OF NEWPORT, KENTUCKY, ASSIGNOR, BY MESNE ASSIGNMENTS, TO UNITED SHOE MACHINERY CORPORATION, OF PATERSON, NEW JERSEY, A CORPORATION OF NEW JERSEY.

METHOD OF MAKING SHOE-BLANKS.

1,361,941.

Specification of Letters Patent. Patented Dec. 14, 1920.

Application filed May 29, 1915. Serial No. 31,260.

To all whom it may concern:

Be it known that I, SAMUEL J. WENTWORTH, a citizen of the United States, residing at Newport, in the county of Campbell and State of Kentucky, have invented certain Improvements in Methods of Making Shoe-Blanks, of which the following description, in connection with the accompanying drawings, is a specification, like reference characters on the drawings indicating like parts in the several figures.

This invention relates to a method of making shoe blanks and will be described hereinafter in connection with the building 15 of a heel for boots or shoes, although it may be practised advantageously in the manufacture of other kinds of blanks used in boot and shoe making.

In the process of heel building, as customarily practised, a plurality of individual lifts, usually of graduated sizes, are pasted and assembled in the form of a heel blank, which is put under pressure for an instant while a nail is driven through the 20 lifts to aid in securing them together. After a considerable quantity of these heel blanks has accumulated, they are piled upon a board, another board is placed upon them and the whole is subjected to pressure in a screw press. Inasmuch as several piles of 25 heels are placed upon the board and there is more or less variation in the heights of the individual heels, it frequently happens that many of the heels receive little, if any, pressure from the screw. Furthermore, a sufficient interval elapses between the building 30 of the first heels and the placing of the accumulation of heels in the press to allow the paste in many of the heels to become 35 more or less set or crystallized and lose its adhesive quality, so that the lifts do not adhere together tightly, no matter how much pressure they may receive. There is 40 a resulting tendency in a considerable portion of the heels to "check," which is very detrimental to the appearance of the shoes to which the heels are attached.

The main object of this invention is to provide a method of assembling and securing together the parts of a heel or other blank in a rapid, economical and effective manner, producing at a minimum cost a blank of superior quality, free from the objectionable features above described.

Broadly considered, one of the most important steps in the process constituting the present invention consists in subjecting a blank composed of a plurality of pieces, such, for example, as a heel blank, consisting of a number of lifts coated with an adhesive and assembled into the desired form, to a plurality of distinct and separate applications of pressure before the adhesive has had time to set or crystallize, whereby the adhesive is quickly rendered tacky and the lifts are caused to adhere together very tightly.

When a gouged or concave lift is included in a heel built according to usual methods, the pressure of the heel press is practically 70 all exerted upon the edge portion of the heel. When the heel is thereafter compressed in the heel compressing machine, wherein a convex die is used to form a concave heel seat and the interior portion of 75 the heel is very heavily compressed, the paste, which has by this time dried and crystallized, is broken up by the substantial shifting of the lifts which occurs in the compressor. The result is that the edges 80 of the lifts are no longer held tightly together and the heel is very liable to check.

Another object of the invention is to overcome the difficulty just mentioned and, accordingly, in one aspect of the invention, 85 a novel method of heel building is provided, in the practice of which a plurality of lifts, including one which is gouged or concaved, are assembled, the edge portion of the heel blank is subjected to pressure 90 and, immediately thereafter, the interior portion of the blank is subjected to pressure in such a manner as to produce a concavity in the heel seat surface before the paste has 95 set or crystallized.

A further object of the invention is to provide a method of shaping or forming shoe blanks by a progressive action involving the application of a series of successive 100 pressures. When this method is practised in building a heel blank, for example, the blank is so shaped and compacted as greatly to facilitate the subsequent operation of the heel compressor or, it may be, entirely eliminate 105 the necessity for that operation.

In the preferred manner of practising the method of my invention, the pile of assembled lifts is subjected to a large number of

successive momentary applications of moderate pressure, and it is preferable to use a suitably formed instrument in applying at least part of the successive pressures, 5 with the end in view of forming the cup or concavity in the heel seat, which has heretofore been made by the heel compressor.

The lifts of the heel produced by my method, when practised in its preferred 10 manner, adhere very tightly together and the heel is very compact. It is substantially free from the tendency to check at the edges and it is so solid and well formed as greatly to facilitate the subsequent operation of the 15 heel compressor, or, it may be, to eliminate entirely the necessity for performing the compressing operation. I prefer, in the practice of my method, to perform all the steps necessary to produce such a product, 20 but it should be understood that one or more of the steps may be omitted without departing from the invention, the scope of which is limited only as defined in the claims.

25 I shall now describe my invention in detail as practised in building a heel for boots or shoes, although it should be understood that its utility is not limited to heel building, but that the method may be practised advantageously in the manufacture of other 30 kinds of shoe blanks.

In the drawings,

Figure 1 shows a heel blank built by the usual method as it appears when taken from 35 the heel press;

Fig. 2 shows a heel in a suitable holding device ready to undergo the first step of the method of the present invention;

Figs. 3, 4 and 5 illustrate succeeding steps 40 of the method;

Fig. 6 shows a completed heel blank built by the improved method; and

Fig. 7 shows a partially assembled heel blank including a gouged or concaved lift.

45 In building a heel by my method, some or all of the surfaces of the heel lifts are coated with an adhesive, which is preferably of a quick drying character, and the lifts are assembled in a pile having substantially the 50 shape of the desired blank. The lifts may be either whole lifts or pieced, and may be made of leather, leatherboard or any other suitable material.

55 After the pile of lifts has been assembled into substantially the desired form, the lifts may be more accurately alined by subjecting them to edge pressure in some sort of clamping device, and it is preferred that this shall be done, but this step is by no means essential to the practice of the method in a broader sense.

Fig. 2 shows a clamping device which may conveniently be used in practising the method. A pair of edge clamping jaws 10 60 is arranged to engage the sides and curved

rear portion of the heel blank 12 in order to aline the lifts and insure that the blank shall be symmetrical in form. The blank may be placed in the clamp by hand or by any suitable automatic mechanism as desired. Now, 70 while the adhesive is still soft and before it has had time to crystallize or set, the heel is subjected to a moderate pressure. This may be done with any suitable or desired form of press. In the drawings, a table 14 is shown, 75 upon which the heel is supported while a reciprocating plunger 16 is caused to descend with sufficient force to exert the required pressure upon the work. The pressure is released after a brief period of time 80 and again applied momentarily, this operation being repeated until the heel has been subjected to a considerable number of successive applications of pressure. The alternate application and release of pressure 85 causes the adhesive to be thoroughly distributed between the lifts and well worked into their surfaces, which are brought into very intimate contact and adhere very 90 tightly together as soon as the adhesive begins to set. I have found by experiment that the application of a succession of moderate pressures to the individual blanks with intermediate periods of release, produces results much superior to those produced by a 95 single application of pressure, even though the latter be very great.

In order to secure the greatest economy in commercial operation I prefer to assemble the lifts by hand and then place the heels 100 one by one in an automatic press which shall exert successive pressures upon them for a period of time sufficient to insure thorough distribution of the adhesive and knitting together of the lifts. The operative is thus 105 able to devote his entire time to the assembling of the lifts, and the production of heels is very rapid. It will be apparent, however, that the method may be performed entirely by hand, if desired.

110 I prefer to use one or more convex dies for exerting at least part of the separate pressures upon the heel blank and find that I am able, by so doing, to secure a well formed cup or concavity in the heel seat by 115 a progressive action with moderate pressure, although exceedingly heavy pressure is required to obtain this result by a single operation in the usual heel compressing machine. In Figs. 3, 4 and 5, I have shown a 120 series of convex dies 18, 20, 22, which have been found in practice to be suitable for use in the practice of my method. It will be observed that the dies are of different degrees of convexity. I prefer first to subject the 125 heel blank to pressure upon the flat table, as shown in Fig. 2, the pressure being exerted upon the edges of the blank, and then to subject it successively to the action of the convex dies 18, 20, 22, which have faces of in- 130

creasingly greater curvature, in the order named, thus exerting increasingly greater pressure upon the interior of the blank. In order to secure the best results, I have, in 5 practice, subjected the blank to a plurality of separate pressures in each of the positions illustrated in Figs. 2, 3, 4 and 5, thus knitting the lifts together and forming the concavity in the heel seat in a progressive manner and obtaining superior results with moderate pressures. The formation of this concavity may be greatly facilitated by following the common practice of building a gouged or concaved lift into the heel, as 10 illustrated in Fig. 7. The process is continued until the adhesive has set sufficiently to prevent separation or loosening of the lifts, after which the blank is ready to be disposed of in any way desired.

20 I contemplate the use of the usual heel building nail to aid in securing the lifts permanently together, if desired, although I have found that by using a suitable adhesive, heels of very high grade may be produced by my novel method without the use 25 of a nail or nails. One of the advantages of the invention lies in the fact that heels are produced, the lifts of which are so well secured together by the adhesive that no 30 heel building nail is necessary, a condition which is desired by many manufacturers.

I have found in practice that heels produced by the novel method herein described are solid, smooth and well formed and are 35 superior in both quality and appearance to a heel made by the ordinary method, which is more or less rough and frequently checks around the edges, as shown in Fig. 1.

An improved machine, by the aid of which 40 my novel method may be advantageously practised is made the subject-matter of an application for Letters Patent of the United States, Serial No. 31,259, filed concurrently herewith, but as above stated, my method is 45 not dependent for its success upon any particular machine or apparatus.

Having explained the nature of my invention and set forth fully how it may be practised, what I claim as new and desire to 50 secure by Letters Patent of the United States is:

1. The method of preparing blanks for boots or shoes which comprises assembling, without the application of pressure, a sufficient 55 number of pieces coated with an adhesive to form a complete blank, and immediately thereafter, before the adhesive has had time to set or crystallize, subjecting the individual blank to a series of distinct and 60 separate applications of pressure separately from and independently of any other blank.

2. The method of building heels which comprises assembling a plurality of lifts coated with an adhesive into the form of a blank and immediately thereafter, before the 65 adhesive has had time to set or crystallize, subjecting the individual blank throughout to a series of successive applications of pressure, the successive applications of pressure on the interior portion of the blank progressively increasing in amount. 70

3. The method of preparing heels which comprises assembling, without the application of pressure, a sufficient number of pasted lifts to form a heel, and immediately 75 thereafter, before the paste has had time to set or crystallize, subjecting the individual heel to a series of distinct and separate applications of pressure progressively increasing in amount. 80

4. The method of building heels which comprises assembling a plurality of pasted lifts, one of which is gouged or concaved, to form a heel, subjecting the edges of the heel to pressure exerted normally to the faces of 85 the lifts, and, immediately thereafter, subjecting the interior portion of the heel to pressure to produce a concavity in the heel seat surface. 90

5. The method of building heels which 95 comprises assembling a plurality of pasted lifts, one of which is gouged or concaved to form a heel, subjecting the edges of the heel to pressure, and thereafter subjecting the interior portion of the heel to a series of progressively increasing pressures to produce a concavity in the heel seat surface. 95

6. The method of building heels which comprises assembling a plurality of lifts pasted with a quick drying adhesive, to form 100 a heel, subjecting the edges of the heel to pressure exerted normally to the faces of the lifts, and immediately thereafter, before the paste has had time to set or crystallize, subjecting the interior portion of the heel to 105 pressure separately from and independently of any other heel.

7. The method of preparing blanks for boots or shoes which comprises assembling a sufficient number of pieces coated with a 110 quick drying adhesive to form a complete blank, immediately thereafter, before the adhesive has had time to set or crystallize, subjecting the individual blank to a rapid succession of distinct and separate applications of pressure separately from and independently of any other blank, and wholly releasing the blank from pressure between 115 successive applications thereof.

In testimony whereof I have signed my 120 name to this specification.

SAMUEL J. WENTWORTH.
